DENTAL HAMMER

Martin Staunt, Chicago, Ill.

Application October 10, 1947, Serial No. 779,191

14 Claims. (Cl. 32—54)

1

The present invention relates to dental hammers and is particularly concerned with dental hammers of a type peculiarly adapted to be used for compacting amalgam fillings, but is also of universal application and may be provided with suitable tools for use on inlays and for other purposes.

One of the objects of the invention is the provision of an improved dental hammer which may be employed with any of a multiplicity of different tools for compacting amalgam fillings, the tool being preferably selected to cover a maximum area of the filling and to conform as nearly as possible to the shape of the exposed area of the filling.

Another object of the invention is the provision of an improved dental hammer which is provided with an improved tool holding device by means of which the tool or hammer is secured against axial movement, and it may also be secured against rotative movement, if desired.

A further object of the invention is the provision of an improved tool holding device for dental hammers which positively locks the shank of the tool in the dental hammer and which may be used for securing the tool against axial movement while permitting the tool to rotate, if desired, or for securing the tool against both axial and rotative movement, except with the parts of the dental hammer.

Another object of the invention is the provision of an improved dental hammer including an angle head which may be turned and secured in any of a multiplicity of angular positions so as to enable the user to adjust the tool into a position where the hammer can act directly on the amalgam filling in a direction which is normal to the surface of the filling.

Another object of the invention is the provision of an improved dental hammer in which the driving teeth of the gears are so constructed that they will always take up the play and wear which is caused by continued use, so that the device may be used for a long period of time without the necessity for replacement of its gears.

Another object of the invention is the provision of an improved dental hammer adapted to press out substantially all of the mercury from the amalgam fillings so that the fillings which are treated with this hammer will be hard and white and more durable than those installed with the devices of the prior art.

Another object of the invention is the provision of an improved construction of dental hammer in which the impact collar has a clear-

2

ance except when a dog hits it, so that the pressure is exerted on the angle head bearing.

Another object of the invention is the provision of an improved dental hammer which may be held lightly and which is adapted to make the work easier and to provide the operator with better control and more efficient action in the compacting of amalgam fillings.

Another object of the invention is the provision of an improved dental hammer which is so constructed that saliva and amalgam is kept out of the bearings of the device and which is durable, capable of economical manufacture, and adapted to be used for a long period of time without the necessity for repair or replacement.

Other objects and advantages of the invention will be apparent from the following description and the accompanying drawings, in which similar characters of reference indicate similar parts throughout the several views.

Referring to the two sheets of drawings accompanying this specification,

Fig. 1 is a fragmentary sectional view taken on a plane passing through the axes of the spindles 25 of the handpiece and its dental hammer attachment;

Fig. 2 is a side fragmentary elevational view of the handpiece with the dental hammer attachment secured to it;

Fig. 3 is an axial sectional view taken through the axis of the angle head for the dental hammer;

Fig. 4 is a front elevational view of the angle head;

Fig. 5 is a side elevational view of the plugger tube assembly shown with the dental hammer;

Fig. 6 is an enlarged axial sectional view of the plugger tube shown in connection with a hammer tool to illustrate the mode of securement of the tool shank;

Fig. 7 is a transverse sectional view taken on the plane of the line 7—7 of Fig. 6 looking in the direction of the arrows;

Fig. 8 is an end elevational view of the plugger tube;

Fig. 9 is an inside elevational view of the cap with the shank position shown in dotted lines;

Fig. 10 is a sectional view taken on the plane of the line 10—10 of Fig. 6 looking in the direction of the arrows with the tool removed;

Fig. 11 is a fragmentary side elevational view of the hammer shaft showing the hammer or dog inside elevation;

Fig. 12 is an end elevational view taken on the plane of the line 12—12 of Fig. 11;

Fig. 13 is a side elevational view of one form of hammer tool;

Fig. 14 is an end elevational view of the tool of Fig. 13;

Fig. 15 is a side elevational view of the cap bearing for the plugger tube;

Fig. 16 is an end elevational view taken on the plane of the line 16—16 of Fig. 15.

All of the views except Fig. 2 are enlarged.

Referring to Figs. 1 and 2, the dental hammer attachment is indicated in its entirety by the numeral 20 and is shown in connection with a dental handpiece 21 to which it is attached. The handpiece 21 is provided with a sheath 22, which supports the front end bearing 23 for the rotating spindle 24. The spindle 24 has a cylindrical bore 25 terminating in a frusto-conical bore 26 for receiving the collet 27.

The collet 27 comprises a sleeve split at each of its ends by slots 28 and having a bore 29 adapted to receive the shank of a driven shaft 30. The collet 27 is engaged at its left end by an actuating member 31, which in turn is engaged by a thrust rod 32 having the usual threaded portion (not shown) by means of which the collet is forced to move axially. The front end bearing 23 is preferably tapered toward its end and has an outer frusto-conical surface 33 and it is provided with a threaded bore 34 for receiving a screw bolt 35.

A screw bolt 35, the head of which projects above the frusto-conical surface, is for engagement with the hammer attachment 20. The front bearing 23 of the handpiece has a cylindrical bore 36, which is in alignment with the bore 29 in the collet so that the shaft 30 of the attachment may enter the front bearing 23 and extended into and through the collet 27, which is adapted to grip the shaft.

The dental hammer attachment 20 is provided with a rear bearing member 37, comprising a substantially cylindrical metal member, which may be made of stainless steel, and all of the outer parts of the dental hammer attachment are preferably made of stainless steel. The rear bearing 37 has a relatively small cylindrical portion 38 at its right end which is provided with a cylindrical bore 39, serving as a bearing for the right end of the shaft 30.

The cylindrical portion 38 carries a reduced cylindrical portion 40, which is provided with threads 41 for engagement with the internal threads 42 on the knee member 43. The rear bearing 37 also has an annular surface 44, which is engaged by the end 45 of the knee 43 when the knee is threaded home on the rear bearing 37.

The left end of the rear bearing 37 is enlarged and provided with an outer cylindrical surface 46 and it is provided with an inner frusto-conical bore 47, which is complementary in shape to the frusto-conical outer surface 33 of the front bearing 23 on the handpiece 21. The enlarged cylindrical portion 46 of the rear bearing 37 has a slot 48 extending into its end edge 49, and the slot 48 is large enough to receive the head of the screw bolt 35, thus the head of bolt 35 prevents rear bearing 37 from rotating on the front bearing 33 of the handpiece 21 while the collet 27 grips the shaft 30 and prevents the attachment 20 from moving axially off the handpiece 21.

When the attachment 20 is secured in the handpiece 21, as shown in Fig. 1, the spindle 24 of the handpiece is adapted to drive the shaft 30 of the attachment.

The frusto-conical bore 47 in the rear bearing

37 terminates at an annular surface 50 and the shaft 30 is provided with a thrust collar 51 secured to it by means of a friction pin 52 for engaging the thrust surface 50. At its other end shaft 30 has a pinion 53 comprising a cylindrical member formed with a flat thrust surface 54 on its left end for engaging the end 55 of the reduced portion 40. The pinion 53 is secured to shaft 30 by means of a friction pin 56 and thus the pinion 53 and collar 51 prevent the shaft 30 from moving axially, but they permit it to rotate within the bearing bore 39.

Pinion 53 is provided with teeth 57, which are preferably relatively sharp and V-shaped. These teeth are complementary to the teeth 58 on the driven pinion 59, which is carried by shaft 60. The V-shaped teeth tend to take up wear and reduce backlash or looseness which might be due to wear between the teeth.

The knee 43 is provided with a bore 61 in alignment with the threaded bore 42 and the bores 61 and 42 are large enough to pass over the pinion 53, thus the knee 43 may be passed over the pinion 53 and threaded on the threaded portion 41 of the rear bearing. The knee 43 also has an angle bore 62 for receiving the pinion 59 and a reduced portion 150 on the bearing member 68.

The reduced portion 150 has an annular surface 63 at its left end for engaging the flat end 64 of the pinion 59. This pinion is also secured to shaft 60 by means of a driven pin 65. The knee 43 has its right end (Fig. 1) provided with a multiplicity of axially extending teeth 66, which are also preferably V-shaped and relatively small in size. Teeth 66 are complementary to similar teeth 67 on the end of the bearing member 68 for shaft 60.

The knee 43 also has a threaded cylindrical portion 69 for receiving a threaded sleeve or ferrule 70. The ferrule 70 has an internal bore 71 with threads for engaging the threads 57 and it has a reduced cylindrical counterbore 72, which is large enough to receive the cylindrical portion 73 of the bearing 68.

The ferrule 70 has an internal annular shoulder 74 facing toward the left and shoulder 74, engages an annular shoulder 75 on the bearing member 68; thus the ferrule 70 may be threaded on the knee 43 and it will draw the teeth 67 of the bearing member 68 into the teeth 66 on the end of the knee 43 until the bearing 68 is fixedly secured to the knee. Before tightening the ferrule 70 the pinion 59 and reduced portion 150 of bearing 68 must be inserted in the angle bore 62 of the knee 43.

The reduced threaded portion 69 of the knee 43 preferably extends off at an obtuse angle to the axis of the shaft 30, and thus the bearing 68 extends at an angle to the handpiece 21.

It is also possible to rotate the bearing 68 and to bring different sets of teeth 66, 67 into engagement with each other, so that the tool 76 may have any rotative position desired by means of the adjustment that is provided between the teeth 66, 67 secured by the ferrule 70. The head of the tool will thus have as many adjusted positions as there are teeth at 66, 67, and the operator may use this adjustment so that the hammer tool 76 will extend in the direction he desires, which is normal to the surface of the amalgam filling, when he holds the handpiece 21 in a position most convenient to him.

The bearing member 68 for shaft 60 also has a reduced threaded portion 77 and an annular

thrust surface 78, and the angle head 79 has a threaded bore 80 for engagement with the reduced threaded portion 77. The end of the angle head 79 engages the thrust surface 78 when the angle head is tightly threaded on the angle bearing 68.

Shaft 60 is provided at its right end with a cylindrical impact collar 82, which forms an integral part of an eccentric dog 83. Both of these members have a bore for receiving the shaft 60 to which they are both secured by a friction pin 84. The impact collar 82 has an outer cylindrical surface 85, and which engages the inner cylindrical bore 86 in the angle head 79; thus any impact which is transmitted by reaction to the dog 83 is resisted by the collar 82 engaging the cylindrical surface of the bore 86 in the angle head 79.

The reaction from the impacts is taken by the angle head instead of the bearing bore 87 in the bearing member 68; thus the bearing will be maintained in a good condition for a long period of time.

The impact collar 82 also serves as a thrust bearing as its flat left side 88 engages the end 89 of the bearing member 68 to prevent axial movement of the shaft 60.

The dog 83 and thrust collar 82 are shown in Figs. 11 and 12 in connection with the shaft 60. Dog 83 comprises a partial cylindrical portion 90 surrounding the shaft 60, but at one side the cylindrical portion 90 is enlarged to form a V-shaped point 91, the ridge of which is slightly rounded and the point 91 is within the boundaries of the cylindrical surface 85 of the collar 82; thus the bore 86 of the angle head 79 will pass over both the dog 83 and the collar 82 when the angle head 79 is threaded on the bearing 68.

The angle head 79 is shown in Fig. 3 and it comprises a metal member, preferably made of stainless steel, having the bore 86 previously described, and another threaded bore 92 at right angles to the bore 86. The threaded bore 92 is located in the tubular portion 93 having a flat end surface 94. Bore 92 is adapted to receive the threaded portion 95 of a cap 96, which had a radially extending cap flange 97 with a non-circular outer edge, such as, for example, an octagonal formation. The head of the flange is adapted to be engaged by a wrench so that it may be threaded tightly into the bore 92.

The bore 92 communicates with a smaller counterbore 98 in the angle head 79, and the counterbore 98 is adapted to receive the bottom bearing 99. Bottom bearing 99 comprises a cylindrical sleeve with an inner cylindrical bore 100, and the sleeve 99 is adapted to fit in the counterbore 98. Sleeve 99 has a cylindrical enlargement 101, which fits in the unthreaded portion of the bore 92 and the cylindrical enlargement 101 is provided with a flat side 102 on the side adjacent to bore 86.

The plugger tube 103 is adapted to slide in the bore 98 of the bottom bearing 99, and plugger tube 103 has an outer cylindrical surface 104. In order to hold the plugger sleeve 103 against rotating, the bottom bearing enlargement 101 has an axial extension 105. This extension has an outer cylindrical surface 106, but has a flat surface 107 on its inner side. The flat surface 107 is adapted to engage a flat surface 105 on the plugger tube 103, so that the plugger tube may slide axially but it may not rotate because of the two flat engaging surfaces 107, 108.

Plugger tube 103 is provided with a radially

extending flange 109, which has a flat annular surface 110 on its left side (Fig. 6). The flat surface 108 is formed by cutting off the flange 109 at the top side of the plugger tube in Fig. 6. The annular surface 110 is located to be engaged by the point 91 of the dog 83, but the plugger tube 103 has a sufficient range of movement so that it may slide toward the right far enough so that the surface 110 is not engaged by the dog 83.

Engagement between the dog 83 and the plugger tube is brought about only by pressing the tool 16 against the work, which pushes the flange 110 backwardly into the angle head 79 until it is struck by the dog 83. Thus the amount of impact may be controlled by the pressure which the operator places upon the tool and the impact ceases when the operator ceases to press the tool against the work.

The plugger tube 103 has a cylindrical outer surface 111 on the right side of the impact flange 109 in Fig. 6. Cylindrical portion 111 is rotatively mounted in the bore 112 in the cap member 96 and the cap member is provided with an end surface 113 that acts as a stop surface for engaging the right side 114 of the impact flange 109, thus determining the range of movement of the plugger tube 103.

Plugger tube 103 is long enough to extend outwardly beyond the cap 96, where it is provided with a reduced cylindrical portion 115. This reduced cylindrical portion supports a cam 116, which is pinned to it by a friction pin 117, and the cam 116 engages an annular shoulder 118. Cam 116 has an outer cylindrical surface 119 for rotatively supporting a lock cap 120. The cylindrical surface 119 of cam 116 is located eccentrically with respect to the axis of the plugger tube 103, and this is accomplished by making the wall of the cam 116 thicker in a radial direction on one side.

The lock cap comprises a cylindrical cup-shaped member having an inner cylindrical bore 121 with a rotating fit on the surface 119 on the cam 116. The outer cylindrical surface 122 of the lock cap 120 is knurled for engagement with the fingers. The lock cap 120 comprises a tubular portion 123 and a flat end wall 124, the tubular portion 123 being rotatively mounted on the cam 116. Tubular portion 123 is provided with a pair of axially extending fingers 125 which may be bent inward as shown in Fig. 6 in engagement with the frusto-conical surface 126 on the cam 116.

Thus the fingers 125 will retain the lock cap 120 on the cam 116. In order to limit the rotative movement of the lock cap 120, the cam 116 is provided with a radially extending lug 127, Fig. 10, which engages fingers 125 and limits the rotation of the lock cap to about one-half rotation. The plugger tube 103 is preferably closed at its left end by means of end wall 128, but it is provided with a cylindrical bore 129 having a sliding fit with the shank 130 of any of a multiplicity of tools 76.

The shank 130 has a flat end portion 131 for engaging the end wall 128 of the plugger tube, so that the impact between the tool shank and the plugger tube is taken by the wall 128. The shank 130 of any tool to be used also has intermediate its ends an annular groove 132, which may be rectangular in cross section, as shown in Fig. 13.

This leaves two annular surfaces 133 and 134 and a reduced cylindrical portion 135, which define the groove 132. Beyond the groove 132 to

ward the right, the working end 136 of the tool may take any of a multiplicity of different shapes. The end surface 137 is shown as being flat and provided with a circular edge 138, and the work end 136 of the tool is joined to the shank of hammer tool 76 by reduced curved portion 139.

I desire it to be understood that a multiplicity of different tools may be used, and the tools may be round, rectangular, concave, convex, depending upon the shape of the surface and the area of the surface of the exposed amalgam of the filling. A tool should be selected which will impact against most of the area of the filling and in sharp corners additional tools of complementary shape will be used to get into those corners and compact the amalgam.

The lock cap 120 has its end wall 124 thinner than the width of the groove 132 in the shank 130; thus the inner side 140 of the lock cap wall 124 may engage the annular surface 133 in the groove 132, but the outer surface 141 of the lock cap is free of the annular surface 134 on the tool. This means that the tool does not transmit impact to the lock cap, but the impact is taken by the end 131 of the tool and the end 128 of the plunger tube 103.

The lock cap 120 rotates eccentrically on the tube 103 and on the cam 116, but the aperture 142 in the lock cap 120 is eccentrically located, so that when the tool shank is in place, as shown in Fig. 6, the lock cap may be rotated until a portion 143 of its wall 124 is locked in the groove 132. The eccentricity of the aperture 142 in the lock cap with respect to its tubular portion 123 is the same in amount as the eccentricity of the cam 116 with respect to the axis of the plunger tube 103. This means that, at a certain point in the rotation of the cap, the aperture 142 can be brought into registry with the bore 129.

The lock cap 120 may thus be rotated to such a position that the aperture 142 is in registry with the bore 129. This is necessary in order that the shank 130 may be inserted in the plunger tube 103. The eccentricity of the aperture 142 in the lock cap 120 is such that the edge of the aperture 102 may be brought into wedging engagement with the reduced cylindrical portion 135 in the groove 132.

When this is done, the wedged condition between the inside of the bore 142 on cap 120 and the tool shank causes the tool shank to be held against rotation. This is desirable, when the working end 136 of the tool has a pointed or angular surface, to get into a corner of the filling cavity. Under such conditions it is not desirable for the tool to turn as the point must be held in the corner of the cavity while the amalgam is made compact.

It is not necessary however to turn the cap 120 until the tool shank is held against rotation. A slight turn of the cap without exerting much force will result in the securement of the tool while permitting it to rotate in the plunger tube 103.

Thus the operator may secure the tool for axial movement with the plunger tube while permitting it to rotate in the plunger tube or he may secure it in the plunger tube so that the tool cannot rotate and as the plunger tube is held against rotation, the tool can only reciprocate.

The operation of the dental hammer is as follows:

The dental hammer attachment has its shaft placed in the collet of the chuck of a dental handpiece 21, where it is secured while the rear bearing 37 is engaged on the front bearing 23

of the handpiece. The bearing member 68 of the hammer attachment may be rotated as desired and adjusted by loosening the ferrule 70 and bringing the teeth 66, 67 into engagement with each other with the bearing 68 in the desired position, where it is secured by threading the ferrule 70 home.

A suitable dental tool is selected and its shank may be inserted in the plunger tube 103 by rotating the cap 120 until its aperture 142 registers with the plunger tube bore 129. The dental tool is then secured by rotating the cap 120 in the opposite direction until the edge of the wall 124 at the bore 142 moves into the groove 132 of the tool shank.

When the spindle 24 of the handpiece is rotated by a suitable motor the collet 21 will drive the shaft 30, which in turn drives its pinion 53. Pinion 53 drives pinion 59, which rotates shaft 60. Shaft 60 rotates collar 82 and dog 83, and the dog 83 is in position to engage the impact flange 109 once for each rotation of the shaft 60, provided the flange 109 is pushed inward far enough to engage the dog.

When the tool 76 is brought into engagement with the work, such as an amalgam filling, this tends to push the tool backward into the angle head, which causes the plunger tube to move inward into the angle head. Then the impact flange 109 brings its surface 110 into the range of movement of the dog 83 and the dog 83 strikes the surface 110 once for each rotation of its shaft, thus producing an impact on the plunger shaft 103 and the tool 76.

The amount of force of the impact depends upon the force or pressure which is exerted by the operator on the work with the tool surface. The ferrule 70 and the reduced portion 38 of the rear bearing 37 and the enlarged portion 46 of the rear bearing 37 are all preferably provided with a plurality of annular grooves 144. These grooves are partially circular in cross section so that there are no sharp corners in which dirt may gather. The grooves are separated by lands 145, the cylindrical outer surfaces of which are preferably knurled, as shown in Fig. 2.

These knurled surfaces and the grooves permit the operator to grasp the hammer attachment more firmly and surely so that it will neither rotate in his hand nor will it slip axially.

The knee member 43 is also preferably provided with a pair of grooves 146 oppositely located so as to provide flat surfaces 147 on the knee 43, by means of which it can be grasped with a wrench or other tool.

It will thus be observed that I have invented an improved dental hammer having an angle adjustment by means of which the working end of the tool may be pointed in any direction, while the dental handpiece itself may extend at an angle to the bearings of the hammer attachment. The present hammer attachment has a simple but positive and secure structure for holding the tool shank, and impact on the tool is not brought to bear upon the tool holding arrangements but is transmitted to a plunger tube which is sturdily constructed to receive it.

The plunger tube is adapted to be engaged by a hammer dog, which, in turn, reacts against a collar that has a wide bearing surface in the angle head, so that the reaction of the impact is not borne by the bearings. The present dental hammer is capable of many different uses, but it is particularly effective in compacting amalgam fillings, because it is provided with suitable

tools for engaging most of the exposed area simultaneously. Thus it presses out substantially all of the mercury and makes the amalgam fillings harder and whiter and more permanent than those which are made by using the devices of the prior art.

While most of the outer parts are preferably made of stainless steel, the angle head is preferably made of brass, which is chromium plated and provided with a stainless steel bearing.

The gears are preferably made of carbon steel and the structure of the device is such that the amalgam and saliva and other foreign matters are kept out of the bearings by the lock cap. Thus the present device may be used for a long period of time without the necessity of repair or replacement of its parts. The device is also easy to take apart so that it may be cleaned and oiled and re-assembled with a minimum amount of labor.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. A dental hammer attachment comprising an angle head having a slidably mounted member for supporting a tool shank, a tool shank in said member, the said shank having an annular groove said member being provided with a cylindrical bore, and said shank being substantially cylindrical, and a rotatable member on said head having an eccentrically mounted portion for movement into said groove on said shank whereby the shank is secured against axial movement with respect to said slidable member the walls of said groove acting as stops for engaging said rotatable member.

2. A dental hammer attachment comprising an angle head having a slidably mounted member for supporting a tool shank, a tool shank in said member, said member being provided with a cylindrical bore, and said shank being substantially cylindrical, and a rotatable member on said head having an eccentrically mounted portion for movement into a groove on said shank whereby the shank is secured against axial movement with respect to said slidable member, said rotatable member comprising a cap eccentrically mounted on said head and having an eccentrically located aperture for receiving the tool shank.

3. In a dental hammer an angle head comprising a metal member having a pair of threaded portions extending transversely to each other and communicating with each other, a bearing member threaded in one of said bores and having a shaft, said shaft carrying an eccentrically mounted impact dog and said shaft carrying an impact resisting collar engaging a complementary bore in said head, and a plunger tube slidably mounted in the other of said bores and having means for supporting a tool, said tube being provided with a radially extending flange for engagement with said dog whereby the rotation of said shaft produces an impact on the plunger tube to move it axially once for each rotation of the shaft, said angle head being provided with a threaded member forming a bearing for one end of the plunger tube and with a cylindrical member housed in the head and forming a bearing

for the other end of the plunger tube, said latter bearing having an axially extending portion provided with a flat surface, engaging a flat surface on the plunger tube to prevent rotation of the plunger tube.

4. In a dental hammer an angle head comprising a metal member having a pair of threaded portions extending transversely to each other and communicating with each other, a bearing member threaded in one of said bores and having a shaft, said shaft carrying an eccentrically mounted impact dog and said shaft carrying an impact resisting collar engaging a complementary bore in said head, a plunger tube slidably mounted in the other of said bores and having means for supporting a tool, said tube being provided with a radially extending flange for engagement with said dog whereby the rotation of said shaft produces an impact on the plunger tube to move it axially once for each rotation of the shaft, and a knee member comprising a tubular metal member having communicating bores extending at an obtuse angle to each other, the end of said knee member being provided with a toothed edge and said head having a bearing member provided with an end having a toothed edge and means for securing the knee member to the bearing carried by the angle head whereby the plunger tube may be extended in any of a multiplicity of different angles with respect to the knee member.

5. In a dental hammer an angle head provided with a pair of threaded bores extending transversely to each other, one of said bores communicating with a cylindrical unthreaded bore, a driving shaft having an enlarged collar for engagement in said unthreaded bore, said collar being integrally secured to an eccentric dog projecting into the other bore, a plunger tube slottedly mounted in said other bore and having a radially extending flange adapted to be engaged by said dog, the reaction from the action of said dog on said flange being transmitted by said collar to said unthreaded bore, said plunger tube being provided with a flat surface on one side and a bearing member mounted in said other bore and provided with a complementary part having a flat surface for engaging the plunger tube and preventing its rotation.

6. In a dental hammer an angle head provided with a pair of threaded bores extending transversely to each other, one of said bores communicating with a cylindrical unthreaded bore, a driving shaft having an enlarged collar for engagement in said unthreaded bore, said collar being integrally secured to an eccentric dog projecting into the other bore, a plunger tube slottedly mounted in said other bore and having a radially extending flange adapted to be engaged by said dog, the reaction from the action of said dog on said flange being transmitted by said collar to said unthreaded bore, said plunger tube having a cylindrical bore for receiving the shank of a tool, a tool having a cylindrical shank located in said bore, said tool having a groove in its shank and an eccentrically mounted member on said plunger tube adapted to rotate into wedging engagement in said groove for securing the tool shank in the plunger tube.

7. A dental hammer assembly comprising a plunger tube adapted to be reciprocably mounted, said plunger tube being provided with an axial bore for receiving the complementary shank of a tool, and a rotatable cap on the end of said tube, said cap having an aperture adapted to

register with said bore in one position whereby a shank may be inserted in the bore, said shank having a groove, said cap being also eccentrically mounted so that it may be rotated until a portion of the cap adjacent to the aperture passes into said groove, whereby the tool shank is held in the plugger tube.

8. A dental hammer assembly comprising a plugger tube adapted to be reciprocably mounted, said plugger tube being provided with an axial bore for receiving the complementary shank of a tool, and a rotatable cap on the end of said tube, said cap having an aperture adapted to register with said bore in one position whereby a shank may be inserted in the bore, said shank having a groove, said cap being also eccentrically mounted so that it may be rotated until a portion of the cap adjacent to the aperture passes into said groove, whereby the tool shank is held in the plugger tube, said cap having a stop member for engaging a stop member on the plugger tube, whereby the cap may be rotated into engagement with the stop member to determine the position of registry of the cap aperture with the bore for easy insertion of the tool shank.

9. In a dental hammer assembly the combination of a rear bearing adapted to receive the front bearing of a handpiece and to be secured thereon with a shaft carried by said rear bearing and adapted to be inserted in the collet of the handpiece and secured therein, said rear bearing having a reduced threaded portion and said shaft being provided with a pinion, and a knee member threaded on said reduced portion and having a bore for receiving said pinion, said knee member having another bore at an obtuse angle to said first-mentioned bore and a second shaft adapted to be moved into said latter bore, said latter shaft being provided with a pinion, both of said pinions being provided with tapered teeth whereby the teeth are adapted to be brought into closer engagement with each other to take up wear and prevent backlash.

10. In a dental hammer assembly the combination of a rear bearing adapted to receive the front bearing of a handpiece and to be secured thereon with a shaft carried by said rear bearing and adapted to be inserted in the collet of the handpiece and secured therein, said rear bearing having a reduced threaded portion and said shaft being provided with a pinion, and a knee member threaded on said reduced portion and having a bore for receiving said pinion, said knee member having another bore at an obtuse angle to said first-mentioned bore and a second shaft adapted to be moved into said latter bore, said latter shaft being provided with a pinion, both of said pinions being provided with tapered teeth whereby the teeth are adapted to be brought into closer engagement with each other to take up wear and prevent backlash, said latter shaft being carried by a bearing member, the end of said latter bearing member and said knee being provided with complementary teeth and a ferrule mounted on said latter bearing member and engaging a shoulder thereon, said ferrule having threads for engaging said knee, whereby the latter bearing member may be secured in any of a multiplicity of rotative positions on said knee.

11. In a dental tool assembly, the combination of a movable shaft mounted for axial sliding movement, said shaft having a cylindrical bore,

a tool member having a cylindrical shank with a sliding fit in said bore, and a rotatable cap eccentrically mounted on said tubular shaft and having an aperture for passing said shank, said shank being formed with an annular shoulder engaged by said cap when the cap is rotated into an eccentric position to retain the tool shank in the shaft.

12. In a dental tool assembly, the combination of a movable shaft mounted for axial sliding movement, said shaft having a cylindrical bore, a tool member having a cylindrical shank with a sliding fit in said bore, and a rotatable cap eccentrically mounted on said tubular shaft and having an aperture for passing said shank, said shank being formed with an annular shoulder engaged by said cap when the cap is rotated into an eccentric position to retain the tool shank in the shaft, said shank also having a reduced cylindrical portion, and said cap being rotatable until its aperture wedges against said reduced cylindrical portion to prevent rotation of the tool shank in said shaft.

13. In a dental tool assembly, the combination of a hand piece attachment adapted to fit on the end of a hand piece housing having a collet, said attachment having an axial bearing bore, a shaft in said bore, and projecting backwardly to be engaged by the collet of the dental hand piece, said shaft having a pinion with axially extending angular teeth, an obtuse angle knee member carried by said attachment, and having a cylindrical bore at each end, said knee member terminating in a threaded tubular part having teeth at the end of said tubular part, a right angle tool supporting head having a pair of cylindrical bores at right angles to each other, one of which supports a tool, and the other of which has a bearing member which supports a shaft for driving said tool, said latter bearing also supporting a threaded bearing, and said bearing having teeth at its rear end for engaging the teeth on the knee member, said threaded bearing drawing said teeth together for fixedly supporting the angle tool supporting head, with the tool extending in any direction relative to the knee member.

14. A dental plugging tool comprising a metal member provided with a head at its working end, and having a cylindrical shank, said cylindrical shank being provided with a plane end for engaging the end of a supporting tube, and the said cylindrical shank having an annular groove that is rectangular in cross section, the said groove being located adjacent the working end of the tool in the cylindrical shank thereof.

MARTIN STAUNT.
